KNITTING MACHINE NEEDLE MOTION

Robert Stewart Erskine Hannay, Edinburgh, Scotland, assignor to F. N. F. Limited, Burton-on-Trent, England

Application February 21, 1948, Serial No. 10,160
In Great Britain June 3, 1942

5 Claims. (Cl. 66—86)

1

This invention relates to warp knitting machines.

In warp knitting machines as now commonly used the knitting needles advance and withdraw endwise, the motion being rectilinear or nearly so. The warp threads are lapped round the hooks of the needles, when advanced, by warp thread guides which are given a to-and-fro swinging motion and a so-called "shogging" motion; that is to say, a motion lengthwise of a zone extending transverse to the mechanism and accommodating one or more rows of the warp thread guides. Generally, a row of knitting needles is associated with a number of rows of warp thread guides, two, three or four being a usual number. The swinging motion of the warp thread guides takes place laterally across the zone in which they are shogged, and this motion involves various difficulties where one is concerned with high speed operation, and the difficulties increase with the number of rows of guides. In effect the swinging motion of the guides may impose a serious limitation of the rate of operation.

An object of the present invention is to operate the support of a row of knitting needles in such a way that the relative motion between the thread guides and said needles can be produced in a simple manner imposing no serious limitations as regards rate of operation and nevertheless permitting a useful number of rows of guides, say as many as four such rows, to be used.

In accordance with the invention, warp knitting mechanism has one or more rows of warp thread guides that are shogged and a row of knitting needles on a support that is given a composite motion in which the needles advance endwise towards the warp thread guides and as they advance swing laterally across the shogging zone of the guides, and in which the needles withdraw endwise, swinging laterally in the return direction. By virtue of the lateral swing of the needles, the thread guides themselves do not require to swing, but merely to shog, in order that the threads will be lapped round the hooks in the knitting operation.

As usual, the needle stems require to work through thread loops at the fell of the fabric being knitted. It is this requirement, together with the position and number of rows of warp guides to be traversed in the swing of the needles, that governs the motion of the needles. Because of the lateral component of the needles' motion as they swing in effect about the fell,

2

the needle stems do not follow the path of their hooks but instead become displaced from said path. In the lateral motion of the hooks, they traverse an adequate zone within which a number of rows of thread guides are positioned and are free to shog in timed relationship with the advance and withdrawal of the needles.

Otherwise stated, the support of the knitting needles is given a composite motion in which the needles advance and withdraw through a line of loops at the fell of the fabric and when advancing and withdrawing swing to-and-fro about said line as axis.

Since by virtue of the invention it is practicable to use warp guides which receive only a shogging motion, another object of the invention is to make provision whereby a simplified construction of warp-guide bars and their operating mechanism can be adopted; by attaining this object, a source of wear and maladjustment, giving a defective product, is eliminated.

The knitting-needle drive may comprise rotary cranks, or the equivalent, which impart to the needles their endwise advance and withdrawal, and mechanism constraining the needles to swing as they advance and retire. The said mechanism may be a link-and-lever assembly, which is operated by the crank or equivalent drive.

Warp-knitting mechanism embodying the invention will now be described by way of example with reference to the accompanying drawings, in which:

35 Fig. 1 is an elevation of the knitting mechanism of a warp-knitting machine. Fig. 2 is a section of a detail, being on the line 2—2 of Fig. 1. Fig. 3 is a sectional elevation of the mechanism, the section being approximately on the line 3—3 of Fig. 1. Figs. 4, 5 and 6 are views of the knitting elements and certain associated parts, as already shown in Fig. 1, but showing them in different positions in the cycle of operations.

45 The knitting elements of the mechanism shown consist of the following: a row of knitting needles 10; a row of tongues 11, there being one tongue per needle; a row of sinkers 12, each with a protuberance 13, every needle being arranged to pass through the space or slot between two adjacent sinkers; four side-by-side rows of warp-thread guides 14. Threads *a* are led through the eyes of the guides 14 to the hooks of the needles 10, and the knitted fabric *b* is led away in the plane in which it is rep-

resented by a dot-dash line (see Figs. 1, 4, 5 and 6).

Each knitting needle 10 is upright or at a varying inclination to upright, having a straight tubular stem, which is embedded at its root in a holding block 15, there being several needles to each block and all the blocks being secured side-by-side along a horizontal needle bar 16. The needle drive is imparted to the bar, 16 through a number of bellcrank levers 17, each having an arm incorporated in the needle bar. The tongues 11 are fine rods which slide through the bores of the respective needle stems, being arranged to co-operate at their top ends with the needle hooks and being clamped at their bottom ends to a horizontal tongue bar 18. The bar 18 is supported by a yoke 19 which is slidably guided at the ends of the needle bar 16. That is to say, the tongues and their bar are movable up and down relatively to the needles and their bar, but not otherwise, the extent of such movement being sufficient to close the tongue tips against the needle hooks and to withdraw said tips inside the tubular stems. The movement of the tongues is under the control of links 20 pivotally connected to the yoke 19. The sinkers 12 are secured to a horizontal bar 21 each end of which is supported by a guide rod 22 passing through a member 23 of the machine frame, the sinkers being movable by cam means comprising a rotary cam-shaft 24, a cam 25 thereon for each guide rod 22, a tappet 26 on each guide rod 22 to contact the associated cam, and a return spring 27 on each guide rod (see Fig. 1). Each sinker is an appropriately shaped blade, and its protuberance 13 engages the fell of the fabric and serves to restrain the latest formed row of loops against entrainment by the needles 10 in their endwise motion during each knitting operation. The warp-thread guides 14 of each row are embedded in blocks 28 secured to one of four horizontal guide bars 29. Each guide bar is carried at each end by a suspensory bracket 30 which is slidably attached to a slide bar 31 above, each guide bar being liftable by its suspensory brackets in relation to its slide bar against the action of a return spring 31A on each of said brackets. Each slide bar 31 is guided at its ends in the frame of the machine, and at one end each slide bar cooperates with the cam edge of a rotary pattern wheel 32, there being one such wheel for each slide bar. As Fig. 3 shows, one end of a slide bar 31 has keys 33 slidable in keyways in a frame member 34, close to which the associated pattern wheel 32 extends. The slide bar (say at its opposite end) has a return spring (not shown) to maintain it in operative engagement with its pattern wheel. The arrangement is such that in the operation of the machine an endwise shogging motion is imparted to the rows of warp-thread guides, so that they lay their threads across the hooks of the knitting needles and also carry their threads from needle to needle in order that the needles shall become lapped by the threads and shall knit and interconnect so-called "pillars" of stitches in the warp threads.

The needle bar 16 has its supporting levers 17 either at opposite ends or at several spaced points along the bar, according to the length thereof, and each of these levers is connected to a link-and-lever mechanism below it, the two or more mechanisms being operated from a rotary driving shaft 35 which is geared through intermeshing gearwheels 36 to the cam-shaft 24. Each mechanism comprises the following com-

ponents: a first rocker-arm 37 with a stationary pivot 38 between members 39 of the machine frame (shown only in Fig. 3), this rocker-arm carrying the fulcrum 40 of the associated bellcrank lever 17 (that is to say, the bellcrank lever has a swinging fulcrum); a second rocker-arm 41 having a stationary pivot 42 (similarly to the rock-lever 37); a connecting rod 43 pivotally connected at one end to the bellcrank lever 17 and at the other end to a crank 44 on the driving shaft 35, said crank being balanced by a counterweight 45; a control lever 46 whose fulcrum 47 is carried by the second rocker-arm 41, so that this lever has a swinging fulcrum similarly to the bellcrank lever 17; a pair of parallel links 48 one of which is pivotally connected at opposite ends to the dependent arm 49¹ of the control lever 46 on the one hand and the dependent arm 49² of the bellcrank lever 17 on the other hand, 10 and the other of which is pivotally connected at opposite ends to the fulcrums 40 and 47, said links forming with said dependent arms of these levers a parallelogram (see Fig. 1) and therefore serving to maintain a constant angular relationship between said levers. The other arm of the control lever 46 is formed as a slider 46² which is slidable in a pivotal controller 49. This controller is formed with a slideway 50 for the slider 46² and has trunnions 51 which are pivoted in stationary members 52 of the machine frame (said members 52 being shown only in Fig. 2). The slideway 50 is formed with small bosses 50¹ between which the slider 46² slides. The mechanism is so designed that, in each revolution of the crank 44, the knitting needles 10 rise (i.e. advance endwise) through the inter-sinker spaces and fall again, and as the needles rise and fall they also swing in one direction with their backs leading and then in the return direction with their hooks leading.

It is important to note that the central plane of the sliding arm 46² of the control lever 46, said plane being represented by the line 2—2 in Fig. 1, must move up-and-down always through the stationary axis of the pivotal trunnions 51 and must swing to-and-fro always about said axis.

By virtue of the construction of the control lever 46 and associated components and of its connection through the parallelogrammic linkage 48, 49 and 17 with the needle bar 16, some plane moving with the needle bar 16 incorporating each bellcrank lever 17 must also rise and fall always through some predetermined stationary axis X (seen as a point where the threads a converge Fig. 1) and must also swing to-and-fro always about said axis X. The plane last referred to is a plane approximately containing the row of knitting needles 10, and the stationary axis X is the line of the last-knitted row of loops in the warp threads a at the fell of the fabric b. That is to say, in the operation of the knitting mechanism the knitting needles rise and fall through the stationary line of loops at X and, in rising and falling, swing to-and-fro about said line as axis X. In this composite motion of the needles, their hooks move up and down along a curved path. This path is represented in Figs. 1, 4, 5 and 6 by a dot-dash line c, which is the approximate path of the outermost limits of the hook of a needle 10. It will be noted that the eyes of the warp-thread guides 14 are practically centred on this path c. Thus, in the ascent and descent of the needles, their hooks traverse the zone of the four rows of thread guides 14. With reference now to the tongues 11, each

link 20 controlling their motion is pivotally connected at an offset point, namely at 53, to the associated connecting rod 43. It is by virtue of this connection that the tongues derive their motion in relation to the needles 10. In effect the pivotal connection 53 describes an elliptical path, and it is the deviation of this path from the rise and fall of the needle bar 16 which defines the sliding motion of the yoke 19 carrying the tongues 11.

Fig. 1 shows the mechanism as positioned at the bottom of the needles' path of motion, this being the stage where a row of new loops is drawn down by the hooks through a newly cast-off row of loops now incorporated in the fabric.

Figs. 4 and 5 show the mechanism at successive stages in the ascent of the needles through the new loops. Fig. 6 shows the mechanism as positioned at the top end of the needles' path, the needle hooks then standing clear beyond the rows of guides 14, one or more of which are at this portion of the cycle shogged across the hooks of the needles to an extent determined by their pattern wheels 32. In the descent of the needles, the hooks engage and become lapped with the warp threads a shogged across them and form the next row of stitches.

The knitting mechanism described with reference to and as shown in the accompanying drawings, being an example, can be modified in any of various respects. For instance, the knitting needles may be of any appropriate type; they may be of the latch type or of the bearded type, in which latter event a presser bar would be provided to close the beards.

In the example described, the withdrawal of the hooks is by substantially the same path as their advance; the return path however may be different from the advance path and the form of either path may be modified if so required by other components of the machine.

The sinkers may be used to introduce wefts into the fell of the fabric being knitted. In the example, the sinkers are withdrawn from the needles for a portion of each knitting cycle sufficiently to give freedom of passage not only for the warps a when being shogged but also for wefts if such are introduced.

In the example described, the warp guide bars do not swing but receive merely a shogging motion. In certain cases however one or more warp guide bars may be swung to a predetermined extent, as demanded by the circumstances.

I claim:

1. Warp knitting mechanism comprising one or more rows of warp thread guides for guiding threads to form loops in a fabric, said loops extending along an axis, means for shogging said one or more rows, a row of knitting needles, a needle support on which said row of knitting needles are mounted, means for giving said needle support a composite motion in which said needles advance endwise towards the thread guides and, as they advance, swing laterally across the shogging zone of the guides, and in which the needles withdraw endwise, swinging laterally in the return direction, said composite-motion-giving means comprising a control mounted to pivot about a second axis parallel to said first-mentioned axis, a control lever constrained by said pivotal control to lengthwise movement in relation to said second axis and to swinging movement about said second axis, a second lever incorporated in said needle support, a parallel linkage interconnecting said con-

trol lever and second lever, a pair of rocker arms carrying the fulcrums of said two levers, and means for imparting to said second lever a swinging motion such that the lateral swinging of said needles is about said first-mentioned axis.

2. Warp knitting mechanism including a row of hooked knitting needles mounted on a pivotal support, one or more rows of warp-thread guides,

10 means for shogging the one or more rows of warp-thread guides in relation to the needle hooks, and link-and-lever mechanism for moving the needles to knit warp threads led to their hooks by said guides into rows of stitches in 15 succession, said link-and-lever mechanism being designed to advance and withdraw the needles endwise to and from said guides through a row of stitches and to swing the needles about said row of stitches as axis so that the hooks 20 traverse the zone of said one or more rows of guides and receive therefrom the warp threads and said link-and-lever mechanism including parallel links that connect said pivotal support with a control device and means constraining 25 said device to a composite motion consisting of endwise movement through a stationary line and swinging movement about said line as axis.

3. Warp knitting mechanism including a row of hooked knitting needles having straight tu-

30 bular stems, one or more rows of warp-thread guides, means for shogging the one or more rows of warp-thread guides in relation to the needle hooks, a row of tongues individually operating through said stems like latches to cast-off stitches

35 from the needles, a rotary member, a connecting rod extending from said rotary member and having a connection with the needles, said rod serving to operate the needles, a linkage from said connecting rod to said row of tongues for

40 moving them in timed relation to the needles, and link-and-lever mechanism connected to said row of needles and said connecting rod for moving the needles to knit warp threads led to their hooks by said guides into rows of stitches in succession, said link-and-lever mechanism being de- 45 signed to advance and withdraw the needles endwise to and from said guides through a row of stitches and to swing the needles about said row of stitches as axis so that the hooks traverse the 50 zone of said one or more rows of guides and receive therefrom the warp threads.

4. A warp knitting machine comprising a needle bar, a row of knitting needles on said bar, said needles being adapted to receive a line

55 of loops on a fabric to be knitted by the machine, warp thread guides for leading warp threads engageable by said needles to said line of loops, a rotary shaft, connecting means between said shaft and bar for giving the needles an endwise movement to and from said guides,

60 and link-and-lever mechanism connected with said bar to superpose on said movement a pivotal movement of the row of needles about said line, said link-and-lever mechanism comprising a pivotal control mounted to oscillate about an axis parallel to said line, a slider constrained by said control to endwise movement combined with pivotal movement about said axis, and a parallel linkage inter-connecting said slider and said needle bar.

5. Warp knitting mechanism having a row of knitting needles for knitting a fabric, the knitting needles having straight tubular stems, a row of tongues individually operating through said stems like latches to cast-off stitches from the

needles, a needle support on which said row of knitting needles are mounted, means for giving said support a composite motion, said means comprising a rotary shaft, a connection between said shaft and said needle support for transmitting thereto a rocking motion in which the needles advance and withdraw through the line of loops last-knitted into the fabric, a pivotal control and a link-and-lever mechanism under the constraint of said control and connected to said needle support so as to superpose on said rocking motion another motion in which the needles, when advancing and withdrawing, swing to-and-fro about said line as axis, a tongue support on which said row of tongues are mounted and which is slidably constrained by said needle support so as to take part in the composite mo-

tion thereof, and a linkage from the connection between the rotary shaft and needle support to the tongue support for moving said row of tongues in timed relation to the needles.
